UNITED STATES PATENT OFFICE.

WILLIAM J. A. LONDON, GEORGE HUNTER PLAINE, AND ROBERT C. ALLEN, OF HARTFORD, CONNECTICUT, ASSIGNEES TO THE TERRY STEAM TURBINE COMPANY, OF HARTFORD, CONNECTICUT, A CORPORATION OF CONNECTICUT.

TURBINE-BLADING.

1,149,658.

Specification of Letters Patent. Patented Aug. 10, 1915.

Application filed October 1, 1913. Serial No. 792,774.

To all whom it may concern:

Be it known that we, WILLIAM J. A. LONDON and GEORGE HUNTER PLAINE, subjects of the King of England, and residents of 5 Hartford, county of Hartford, State of Connecticut, and ROBERT C. ALLEN, a citizen of the United States, and resident of Hartford, county of Hartford, State of Connecticut, have invented certain new and useful 10 Improvements in Turbine-Blading, of which the following is a specification.

This invention relates particularly to a novel means for securing the blades or vanes to a rotor.

15 In the drawings, Figure 1 is a side view of part of a rotor, showing one blade secured in position, and another blade ready to be secured in position. Fig. 2 is a transverse sectional view thereof on the line 2—2 20 of Fig. 1. Fig. 3 is a sectional view on the line 3—3 of Fig. 2.

Referring to the drawings, *a* denotes the body of the rotor, the periphery of which is transversely slotted at regular intervals, as 25 indicated at *b*. In each face of the rotor near its edge is a circumferential groove *c*.

d denotes a blade or vane, and *e* the root which is flat on its front face and of irregular formation on its rear face. The thickness 30 of the root is less than the width of the slot in which it fits, and a packing piece *f* is fitted into the slot back of the root, the front face of the packing piece being shaped to correspond with the rear face of the root, 35 and the rear face of the packing piece being flat to fill in the slot. The edges of the packing piece and root extend into the grooves *c* on the front and rear face of the rotor.

40 After all the blades have been assembled with their packing pieces, a setting tool spreads the roots and packing pieces into the grooves so that they lap the walls of the grooves at either side of the slots, securely 45 locking the blades against either radial or lateral displacement. Of course a blade cannot move respectively to the packing piece owing to the fact that the contacting faces between the blade root and packing 50 piece are of irregular shape. This construction produces a very secure fastening of the blades to the body of the rotor, and one

which is quite inexpensive. It is also possible to replace a broken or worn blade with little trouble, as compared with the security 55 and strength of the built-up structure.

Of course it is understood that the outer ends of the blades may be shrouded in any desired manner as is usual in structures of 60 this sort.

We claim as our invention:

1. In a blade fastening device, the combination with a rotor body having transverse peripheral slots, and grooves in the sides intersecting the slots, of blades whose roots are located in the slots, and packing strips located in the slots at one side of the roots, said roots and packing strips being upset to interlock with the walls of the 70 grooves.

2. In a blade fastening device, the combination with a rotor body having transverse slots in its periphery, and grooves in its sides intersecting said slots above their bottom, of blades provided with roots of irregular cross-section fitting in said slots, packing strips filling said slots at one side of said roots, said roots and packing strips being interlocked with the walls of said grooves. 75

3. In a blade fastening device, the combination with a rotor body having transverse peripheral slots with straight walls, of blade roots and packing strips fitting in and filling said slots, the contacting faces of said roots and packing strips being of 85 irregular contour, the edges of said roots and packing strips being displaced within the grooves to interlock with the walls thereof.

4. In a blade fastening device, the combination with a rotor body having transverse peripheral slots and grooves in the sides intersecting the slots, of blade roots and packing strips fitting in and filling said slots, said packing strips being split and 95 rolled over to interlock with the walls of the grooves.
